WILLIAM H. MILLSPAUGH, OF SANDUSKY, OHIO, ASSIGNOR TO THE PAPER & TEXTILE MACHINERY COMPANY, OF SANDUSKY, OHIO

TRAVERSABLE SUCTION ROLL FOR PAPER-MAKING MACHINES

Application filed August 25, 1928. Serial No. 301,995.

The invention to be hereinafter described relates to a traversable suction roll for paper making machines.

In paper making machines the making wires must be periodically renewed, as is well understood. This requires time and labor and means heavy expense in the lost production of the machine during the period over which it must be shut down for the change. 10 Many wire changing mechanisms have been devised in as many attempts to solve the problem. The present invention, however, attacks the difficulty from a different angle. In the present case, the suction roll itself, is 15 slid laterally through and out of the frame, the looped wire dropped vertically into line with the free end of the roll and the roll returned. The job is then completed.

In order to more clearly disclose the construction, operation, and use of the invention, 20 reference should be had to the accompanying drawings forming a part of this application. Throughout the several figures of the drawing like reference characters designate the 25 same parts in the different views.

In the drawings:—

Fig. 1 is a front view, in diagram, of one form of machine to which the invention may be applied.

30 Fig. 2 is an enlarged fragmentary sectional view of Fig. 1, showing the two transfer rolls and traversing mechanism in elevation.

Fig. 3 is a left hand end view of Fig. 2.

Fig. 4 is a right hand end view of Fig. 2, 35 showing traversing roll, only, with suction pipe omitted.

Fig. 5 is a longitudinal cross section on line 5—5 of Fig. 4, looking in the direction of the arrows.

40 In the present instance, the invention has been shown as applied to a paper making machine in which the making wires travel in a generally vertical direction or plane in contradistinction to the regular standard Four-drinier in which the wire travels in a generally horizontal direction or plane. Such vertical arrangement is set forth in detail in my pending application Serial Number 29,600 filed May 11, 1925, to which reference may be 45 had for such features which, however, as to

details, form no part of the present invention. In the particular application of the invention illustrated, a transfer suction roll is used in the invention. The suction rolls on which the web is formed—the forming 55 rolls—are not provided, in the machine shown with the invention.

Referring to the drawings in detail 1 indicates a forming roll about which a making wire 2 passes. In the particular instance 60 shown, there are two forming rolls and wires, the two wires slightly converging to the lower end, with suitable tension rolls for each wire. In the lower end of one wire is a guide roll 3. In the lower end of the other wire is a suction 65 transfer roll 4 which acts, also, as a lower guide roll for that wire. As will be seen in reference to Fig. 1, the rolls 3 and 4 are so positioned in their respective wires that the two wires run together or in travelling contact for a short distance around the first part of the arc of contact or engagement between the suction transfer roll and its wire. In that part of the arc is placed the suction box or chamber which simultaneously bonds the two 70 webs and transfers one from its wire to the wire of the transfer roll. A second suction transfer roll 5 takes the bonded or two ply web from the wire to a press felt 6.

The above is intended merely as a brief outline of the general construction and arrangement of the parts of the machine of the type selected as one illustration of an application of the invention.

The present invention has to do particularly with suction transfer roll 4 and its related cooperating parts in relation to the removal and replacement of the making wire. To that end, Figs. 2 to 5 disclose the details of construction on an enlarged scale. Referring to these figures in detail, the suction transfer roll 4 has a considerably extended head for its rear end, one portion extending much further into the shell end than in the usual standard roll, for a purpose to be later disclosed, while the remainder projects considerably farther outwardly beyond the shell and to provide ample room for two considerably spaced parallel bearings 7 and 8 between which is secured the regular standard driving 85 90 95 100

gear 9 similar to those on the regular suction rolls in general use. The construction of the suction roll itself, except as to the head at the rear end is well known and need not be given here. At the opposite end the usual head and bearing are provided and the usual removable or "loose" piece 10. At the rear end, the two spaced bearings 7 and 8 are securely fixed on a carriage, the bearing 8 being provided with a foot plate 8' by which that bearing may rest upon and be secured to the machine frame—see Figs. 2 and 5. Suitable bolts or other connecting means may be used for this purpose, as will be readily understood. Incidentally, it might be mentioned, that the roll is shown in its operative position in Figs. 2 and 5.

The carriage 11, on which bearings 7 and 8 are mounted, is of inverted U shape in lateral cross section and extends the full length of the two bearings and intervening space. It is supported by and upon parallel, spaced, oppositely directed channel beams 12. The beams 12 are mounted on a common lateral pivot providing a vertical rocking movement at that end. As shown in the drawings it is a well known form of rocker pivot. The opposite ends which extend inwardly beneath the bearings 7 and 8, when the roll is in operative position, are adjustably supported on a small cross rod or lateral bar 14 seated in a suitable yoke 15 on the upper end of a suitable screw-jack. Obviously other elevating means may be used, that shown being merely one well known type. Thus, it will be seen that raising rod 14 will raise the inner end of the beams 12, swinging them on pivot 13. Necessarily, the carriage 11, bearings 7 and 8 and roll 4 will be moved. To provide anti-friction, free-running engagement between the carriage and supporting beams, trolley wheels or rollers 16 are provided, one pair for each beam. They are mounted in any suitable and well known manner on the inner faces of the vertical carriage members in position to engage the horizontal members of the channel beams, while, at the same time, having their inner ends slightly spaced from the vertical walls of the channel beams, all as clearly shown in Fig. 4. Note should be made that the rollers are so disposed that when the beams are in a true horizontal position, the rollers or trolleys do not actually engage the horizontal or tread members of the channel beams. Instead, there is just a very slight space between. Thus when the connecting bolts have been removed from the foot-piece 8' and the jack is operated, on the first slight upward movement, the roll, with its carriage will be rocked vertically upward about its front end, to just about the same extent that the beams will be rocked vertically about their rear ends. The movement, in both cases, is extremely slight, as will be under-

stood. This movement takes up the very slight distance or space between the rollers and their respective treads or channel beam flanges, bringing each in engagement with its respective tread, as will be clear. At the same time, it raises the weight of the roll from the loose piece 10. The beams thus slightly raised are on a very minor incline outwardly toward the rear pivot point 13. In this position, the roll is readily started and easily run out on its beams. When out, the loop of the new wire is simply let down vertically through the frame into line with the suction roll end and the roll run back through the loop, its free end positioned to rest on the loose piece and the jack lowered to its initial position.

As an adequate support for the bearing carriage, when the roll is in operative position, a pedestal 17 is provided. It acts, really, as a separate frame member in sustaining the weight of the roll. It is positioned close to the frame, directly beneath that end of the carriage which supports the rear bearing 7, when the roll is in operative position. It has a relatively wide base and substantially inverted U shaped upper end, the upper end being so proportioned and disposed as to fit between the beams 12 and seat the corresponding end of the carriage 11, at the instant that the roll reaches horizontal or operative position. On slight further downward swing of the beams, their horizontal flanges will disengage the rollers 16 and, at the same time, the beam ends will engage and rest upon a horizontal web 18 of the machine frame, so that the weight of the beams will be off of the jack and supported on the web and pivot at opposite ends, respectively, as will be clear. Likewise, it is obvious that, when in operative position, the entire weight of the roll and carriage is firmly supported by the machine frame, including the pedestal 17, no part of it being sustained by the beams 12.

As will be noticed in reference to Fig. 1 the wire as it passes from roll 4 to roll 5 is deflected toward 4 by 5. In other words, roll 5 in its operative position would be in the path of the lower end of the new wire when that wire is dropped into position to receive the roll 4. To avoid this, the bearings of roll 5 are bolted or otherwise secured to blocks 18 slidably mounted on suitable ways on the machine frame and operable toward and from the roll 4 by hand screws 19 or the like threaded through a frame member and into the respective block. So, when a wire is renewed, the roll 5 may be easily and quickly slid out of the path of the wire loop.

Of course the wire must be placed within the machine frame and passed over the forming roll before it is let down so that its lower loop may receive the roll 4. For this pur-

pose, the upper portion of the frame is provided with a member 19 pivoted at one end and detachably bolted at the opposite end. When the wire is to be renewed, the vat is drained, deckles moved back, and front end bearing of the forming roll removed, all as will be readily understood. Then the tensioning rolls are taken out and the member 19 swung outwardly on its pivot. Next the roll 4 is run out on beams 12 and roll 5 drawn out of the path of the wire. With the parts in these positions the new wire is passed into the frame, over the forming roll and dropped down so that its lower loop is in position to receive the free end of roll 4. The various parts are then all returned to their respective operative positions, as will be readily understood.

In the machine selected for illustration, a pair of converging wires has been shown. It is evident that a single wire or a greater number than two wires may be used and that they may be variously disposed otherwise than as shown. It will also be evident that the invention may be applied to other types of machines than the one shown and to various other machines with their making wires arranged and running differently than in the single instance shown. Many changes may be made in the construction, arrangement, and disposition of the several parts of the invention without departing from the field thereof and, within the scope of the appended claims, it is meant to include all such within this application.

Having thus described my invention, what I claim and desire to protect by Letters Patent is:—

1. A traversable suction roll for paper making machines comprising, a suction roll, and means permitting travel of said roll relatively laterally of the machine and independently of the rest of the machine.

2. A traversable suction roll for paper making machines comprising, a suction roll, a carriage for said roll only, and a track for said carriage.

3. A traversable suction roll for paper making machines comprising, a suction roll, a carriage therefor, a track for said carriage, and means for inclining said track.

4. A traversable suction roll for paper making machines comprising, a suction roll, a carriage therefor, a movably mounted track for said carriage, and means for inclining said track.

5. A traversable suction roll for paper making machines comprising, a suction roll, a carriage therefor, a pivotally mounted track for said carriage, and means for swinging said track on its pivot to incline it.

6. A traversable suction roll for paper making machines comprising, a suction roll, a carriage, an extended bearing connection between said roll and carriage, a track on

which said carriage travels, and means for inclining said track longitudinally.

7. A traversable suction roll for paper making machines comprising, a suction roll, a carriage, a track for supporting said carriage, and means independent of said track for supporting said carriage.

8. A traversable suction roll for paper making machines comprising, a suction roll, a carriage carried by said roll, a track for said carriage, means for inclining said track, and means carried by said carriage and adapted to engage said track and bodily lift said roll, as said track is inclined.

9. A traversable suction roll for paper making machines comprising, a suction roll, a carriage therefor, a track for said carriage, track engaging elements carried by said carriage, and means for moving said engaging elements into engagement with said track.

10. A traversable suction roll for paper making machines comprising, a suction roll provided with extended bearings at one end, a pair of pivotally mounted supporting beams, a carriage connected to said extended bearings and straddling said beams, elements carried by said carriage and normally out of engagement with said beams and means for moving said beams to cause engagement between said elements and said beams and consequent lifting of said roll.

11. A traversable suction roll for paper making machines comprising, a suction roll provided with extended bearings, a carriage connected to said extended bearings, movably mounted supporting beams, elements carried by said carriage normally out of engagement with said beams and adapted to be moved into engagement therewith, and means for rocking said elements into such engagement and, through such engagement lifting said roll.

12. A traversable suction roll for paper making machines comprising, a suction roll provided with an extended bearing, a pair of pivotally mounted supporting beams, a carriage secured to said bearing, elements carried by said carriage and adapted to engage said supporting beams at relatively diagonally disposed points, and means for moving said beams to cause raising or lowering of said carriage and roll.

13. A traversable suction roll for paper making machines comprising, a suction roll, a supporting track, a carriage connected to said roll and adapted to travel on said track, and means adapted to create a binding contact between said track and said carriage whereby the roll may be bodily lifted.

14. A traversable suction roll for paper making machines comprising, a suction roll, a pair of parallel pivoted and spaced supporting beams, a pedestal disposed between said beams, a carriage connected to said roll and adapted to travel on said beams and also

- adapted to be supported on said pedestal, and means for raising said beams to incline the same to remove said carriage from said pedestal.
- 5 15. An independently laterally traversable cantilevered suction roll.
16. In combination, a cantilevered suction roll for paper making machines, and a traversable carriage supporting the same.
- 10 17. In combination, a cantilevered suction roll for paper making machines, and a traversable gravity actuated carriage supporting the same.
- 15 18. In a combination, a cantilevered suction roll for paper making machines, a gravity actuated carriage supporting the same, and means for gravitating said carriage.
- 20 19. In a combination, a cantilevered suction roll for paper making machines, a traversable carriage supporting the same, and means for inclining said carriage to cause gravity actuation of the same.
- 25 20. In combination, a suction roll for paper making machines, and a tilttable carriage supporting the same.
- 30 21. In combination, a suction roll for paper making machines, a tilttable carriage supporting the same, and means for tilting said carriage.
22. In combination, a cantilever suction roll for paper making machines, and a tilttable carriage supporting the same.
- 35 23. In combination, a cantilever suction roll for paper making machines, a tilttable carriage supporting the same, and means for tilting the same.
- 40 24. In combination, a suction roll for paper making machines, a tilttable carriage supporting the same, a track supporting said carriage, and means for tilting said carriage.
- 25 25. In combination, a suction roll for paper making machines, a track and a roll supporting carriage on said track and having a tilttable relation thereto.
- 50 26. In combination, a suction roll for paper making machines, a tiltably mounted track, and a roll supporting carriage on said track and having a tilttable relation thereto.
- 55 27. In combination, a suction roll for paper making machines, a tiltably mounted track, and a roll supporting carriage on said track and having a tilttable relation thereto.
28. In combination, a cantilevered suction roll for paper making machines, a track, and a roll supporting carriage on said track and having a tilttable relation thereto.
- 60 29. In combination, a cantilevered suction roll for paper making machines, a tiltably mounted track, and a roll supporting carriage on said track and having a tilttable relation thereto.
- 65 30. In combination, a roll for paper making machines and a tilttable carriage supporting the same.
31. In combination, a cantilevered roll for paper making machines, and a tilttable carriage supporting the same.
32. In combination, a roll for paper making machines, a tilttable rail, and a carriage for supporting said rail, said carriage being tiltably mounted on and relatively to said rail.
33. A method of mounting wires in a paper making machine comprising removing a roll from its position in the machine frame, passing one loop of a wire over a second roll normally positioned relatively higher in the machine frame than the first roll, suspending said wire from said second roll so that its lower loop will fall in the path of travel of the first mentioned roll, and returning said first roll into said lower loop.
34. A method of mounting wires in a vertical wire type of paper making machine comprising removing a roll from its position in the machine frame, opening a gap beneath one end of a second roll normally positioned relatively higher in the machine than the first roll, passing a wire through said gap and over said second roll, suspending said wire from said second roll so that its lower loop will fall in the path of travel of the first mentioned roll, and returning said roll into said lower loop.
35. A method of mounting wires in a vertical wire type of paper making machine comprising transversely removing a roll from its position in the machine frame, passing one loop of a wire over a second roll normally positioned relatively higher in the machine frame than the first roll, suspending said wire from said second roll so that its lower loop will fall in the path of travel of the first roll, and transversely returning said first roll into said lower loop.
36. A step in the method of mounting wires in a vertical type of paper making machine comprising passing one loop of a wire over an upper roll and suspending said wire from said roll in looped formation to receive a second roll.

Signed at Sandusky, Ohio, this 16th day of August, 1928.

WILLIAM H. MILLSPAUGH.
